UNITED STATES PATENT OFFICE.

OTTO H. HARTMANN, OF CASSEL-WILHELMSHOHE, GERMANY, ASSIGNOR TO SCHMIDT'SCHE HEISSDAMPF-GESELLSCHAFT M. B. H., OF CASSEL-WILHELMSHOHE, GERMANY, A CORPORATION OF GERMANY.

HIGH-PRESSURE STEAM-BOILER PLANT FOR PORTABLE ENGINES.

Application filed September 12, 1924, Serial No. 737,311, and in Germany January 28, 1924.

My invention relates to steam boiler plants, particularly those of a portable or travelling character and has been designed especially for use in conjunction with locomotive engines. Locomotive boilers are at present exclusively of the fire tube type; this, however, is not suitable for pressures above 16 atmospheres and the present invention intends to provide a boiler plant capable of developing live steam of a pressure well above 16 atmospheres, and particularly 30 atmospheres and over. Various other types of boilers have been suggested for use under the conditions just referred to, but such other types do not permit of the ready reconstruction and remodelling of existing locomotives and are therefore available only for new constructions. My present invention has for one of its objects to enable existing locomotives or other travelling engines to be converted readily into boiler plants supplying steam at pressures of 30 atmospheres and more. According to my present invention, two boilers are employed, one of them being constructed as a fire box, and used to supply live steam of at least 30 atmospheres, while the other boiler is employed for supplying steam of up to about 20 atmospheres. The steam produced in these two boilers or generators is conveyed to different stages of a multiple expansion engine. The second boiler, which supplies steam at a lower pressure than the first, may be a fire tube boiler, and thus the existing fire tube boiler of usual locomotives may be utilized for converting such locomotives into improved ones embodying my invention. Thus existing locomotives may be converted readily into high pressure locomotives, by the addition of a separate high pressure boiler and certain other changes that will appear from the description hereinafter. Among these changes, I will mention the provision of a special fire box for the fire tube boiler and the provision of a high pressure cylinder in addition to those in use originally, or instead of this, a new set of cylinders may be provided. The high pressure steam coming from the fire box is then conveyed to the high pressure cylinder or cylinders and allowed to expand therein down to the pressure usually employed for the live steam of existing locomotives, for instance, to about 16 atmospheres. The exhaust steam of the high pressure stage is then mixed with the steam generated in the fire tube boiler and the mixture is then employed as the motive agent in the subsequent stages of the engine. The new high pressure locomotive requires no material alterations in the present way of constructing or operating it and yet will show an advantage of from 25 to 35% as compared with existing locomotives, either in horse power hour, or if no increase in horse power is desired, a corresponding saving in fuel will be effected. Even converting existing locomotives into high pressure locomotives according to the present invention will enable the fuel consumption to be reduced about 20%. The weight of the locomotive is not increased and there are no difficulties as regards the arrangement of the boiler or of the engine proper. It is well known that engines employing a high initial steam pressure will yield better results if operated with intermediate superheating of the steam; such intermediate superheating can be carried out very readily with fire gases of the locomotive when constructed according to this invention, since the difficulties experienced with stationary engines on account of questions of available space, do not arise with locomotive engines.

The generation of steam may be by direct or indirect heating. While the invention has been designed especially for locomotive engines, I desire it to be understood that it is suitable for all sorts of portable or travelling boiler plants, for instance, those of portable engines, ships, or vehicles of all kinds.

In the accompanying drawing, Fig. 1 is a longitudinal section of a locomotive engine embodying my present improvement, and Figs. 2 and 3 are cross sections on the lines 2—2 and 3—3 respectively of Fig. 1.

A indicates the fire box of the engine, constructed of a system of tubes constituting together a high pressure steam generator. The drawings show these tubes as located at the sides and top of a fire box or furnace in which fuel is burned in any suitable manner, for instance, upon grates as indicated in Figs. 1 and 2. This boiler A is intended to supply steam at a pressure of at least 30 atmospheres and the construction is such that pressures of 80 atmospheres and even higher may be obtained readily. At d, I have indicated the upright pipes forming the side walls of the fire box, the steam generated in these upright pipes

passing to the longitudinal collectors *g*, located at the upper ends of the pipes *d*, while the lower ends of said pipes are connected with longitudinal collectors *f*. At the upper portion of the locomotive above the fire box, I have indicated a steam and water drum *e* within which is located a heating coil arrangement *h* connected at its upper portion with the collectors *g*. The lower portion of the heating arrangement *h* is connected with tubular vessels *k*, from which conduits *i* lead to the lower collectors *f*. Thus, the water or other medium employed in this part of the structure will circulate within the parts *f*, *d*, *g*, *h*, *k*, and *i*. From the drum *e* a conduit *l* leads to the saturated steam chest *m'* of a superheater *C*. The chests *m* containing the superheated steam are connected with the high pressure cylinders *E* by a conduit *n*. Another conduit *o* leads from each of these cylinders to a pipe *p* affording a connection to the low pressure cylinders *F* and also affording another connection to the superheater *D*, which heats the steam coming from the boiler *B*. This latter boiler may be a fire tube boiler of the usual type supplying steam at a pressure of say 16 atmospheres. From the steam dome of this boiler, a pipe *s* conveys the saturated steam to the superheater *D*. From the low pressure cylinders, a conduit *q* leads to the blast pipe *r*.

The drum *e* is provided with a safety valve *t* connected with the boiler *B* by a conduit *u* in such a manner that any excess of pressure arising in the drum *e* may be relieved by the passage of steam into the boiler *B*.

H indicates a feed water pump which takes a portion of the water contained in boiler *B*, through a pipe *v* and delivers such water as feed water to the high pressure boiler *A*, through a conduit *w*. In view of this arrangement, the deposit of boiler scale will take place largely in the boiler *B*, thus relieving the high pressure boiler *A* of such deposits.

It will be seen that in the example illustrated and described above, the high pressure steam generated by utilizing the heat of the fire box is produced in the drum *e* by indirect heating. It will be understood, however, that this is only an example, and that the high pressure steam might be produced in the fire box generator by direct heating. In any event, the level of the water is higher in the fire box generator in which the high pressure steam is produced than in the boiler *B* in which the low-pressure steam is generated, and the water and steam spaces of said high pressure generator are separate from those of the low pressure boiler.

The boiler plant described above operates as follows: In the fire box *A*, the radiant heat and the heat of the combustion gases are absorbed by the heat carrying medium (water) circulating through the parts *d*, *f*,

g, *h*, *i*, *k*, and in the coil or equivalent heat transferring device *h*, the heat of this heat carrier is transferred to the water in the boiler or drum *e*, so that high pressure steam (30 atm. or over) is produced in said boiler *e*. After thus producing high pressure steam with the aid of the heat carrying medium circulating through the path indicated above, the combustion gases enter the fire tubes or smoke tubes of the boiler *B* and pass there through to the smoke box to finally escape through the stack. In this boiler *B*, the steam of comparatively low pressure is produced. If the boiler *B*, is constructed for generating steam at the customary pressure of about 16 atmospheres, it is advisable when using such a boiler in conjunction with my invention, to operate at a somewhat lower pressure, for instance, about 13 atmospheres. Should the boiler *e*, heated by means of the fire box *A*, temporarily generate more steam than required for the operation at that moment, the excess steam may be passed to the boiler *B* through the valve *t* and the conduit *l*. The boiler *B* will therefore then serve as a storage receptacle or accumulator. The combustion gases flowing through the smoke tubes of the boiler *B* serve not only for the generation of steam but also for superheating the steam coming from the high pressure section *A* as well as the steam coming from the low pressure section *B*. In the particular embodiment illustrated, the superheater *D* has been shown as of the type in which the smoke flues are comparatively large, while for the superheater *C*, I have shown a construction using comparatively small smoke flues. The exhaust steam from the high pressure cylinder *E* becomes mixed in the conduit *p* with the steam coming from the boiler *B* by way of the superheater *D*, and this steam mixture then enters the cylinders *F*, see Fig. 3, from which it passes through the conduit *q* to the blast pipe *r*. Check valves *z* located in the conduits *p* prevent the passage of the exhaust from the high pressure cylinders to the superheater *D* and the boiler *B*, if, for any reason, this exhaust should be of a pressure higher than that prevailing in the boiler *B*. In this manner, I obtain the advantage that the oil contained in the exhaust of the high pressure stage will not reach the superheater with the attending danger of having the oil burn and stick to the walls of the superheater, and the oil is also utilized for the lubrication of the low pressure stage. Furthermore, the superheat contained in the exhaust is not lost, as it would be if the exhaust were allowed to come in contact with the saturated steam or with the water contained in the boiler *B*.

Mixing the low pressure steam coming from the boiler *B* and superheater *D*, with the exhaust steam of the high pressure stage, insures an effective superheating of the steam admitted to the low pressure cylinders. The

check valves also, to a certain extent, regulate automatically the steam supply to the low pressure stage.

The fire box A serving as a high pressure boiler or as part of such boiler, occupies a space about equal to that of the usual fire box. Should it be necessary in any particular case to enlarge this space, the boiler B could be shortened correspondingly. If the fire box is 10 made with a heating surface of proper area, the reverse connections at the ends of the superheater elements can be arranged close to the front flue sheet of the boiler B without any detrimental effect and thus effective superheating of the steam of both boilers may be obtained.

It will be obvious that various modifications may be made without departing from the nature of my invention.

20 I claim:

1. In a locomotive a steam engine having a plurality of stages operating at different pressures, a water tube fire-box boiler constructed to produce steam of a pressure of at least thirty atmospheres, a horizontal smoke tube boiler heated by the hot gases of the fire box, said smoke tube boiler being constructed to generate steam of a lower pressure, a connection for conveying steam from the water tube fire-box boiler to the high pressure stage of said engine, another connection for leading steam from the smoke tube boiler to the low pressure stage of said engine, a further connection for leading the exhaust steam of 35 said high pressure stage to said low pressure stage, and separate devices for superheating the steam produced in the respective boilers, at least one of said devices being located in the smoke tubes of the smoke tube boiler.

40 2. In a locomotive a steam engine having a plurality of stages operating at different pressures, a high pressure boiler, a smoke tube boiler adapted to generate steam of a lower pressure than the high-pressure boiler, a connection for conveying steam from the high pressure boiler to one stage of said engine, another connection for leading steam from the smoke tube boiler to a subsequent stage of 45 said engine, and separate devices for superheating the steam produced in the respective boilers, one of said devices being located in the smoke tubes of said smoke tube boiler.

50 3. In a locomotive a steam engine having a plurality of stages operating at different pressures, a fire-box boiler constructed to produce steam of a pressure of at least thirty atmospheres, a smoke tube boiler heated by the hot gases of the fire-box, said smoke tube boiler being constructed to generate steam of 55 a lower pressure, connections for conveying the steam from the respective boilers to different stages of said engine, and separate devices located in the smoke tubes of said smoke tube boiler for superheating the steam produced in the respective boilers.

4. In combination a steam engine having a plurality of stages operating at different pressures, two boilers, one adapted to generate steam of a higher pressure than the other which latter is a smoke tube boiler having smoke tubes of normal and enlarged diameter respectively, a connection for conveying steam from the high pressure boiler to one stage of said engine, and another connection for leading steam from the low pressure 70 boiler to a subsequent stage of said engine, and separate devices for superheating the steam produced in the respective boilers, the superheating devices for the high pressure steam being located in boiler smoke tubes of 75 normal diameter, while the superheating devices for the low pressure steam are located in smoke tubes of enlarged diameter.

5. In combination a steam engine having a plurality of stages operating at different pressures, two boilers, one adapted to generate steam of a higher pressure than the other which latter is a smoke tube boiler having smoke tubes some of which are of larger diameter than others, and connections for conveying steam from the high pressure boiler to one stage of said engine, and another connection for leading steam from the low pressure boiler to a subsequent stage of 90 said engine, and separate devices for superheating the steam produced in the respective boilers, the superheating devices for the high pressure steam being located in boiler smoke tubes of smaller diameter than those in which the superheating devices for the lower pressure steam are located.

6. In a locomotive a steam engine having a plurality of stages operating at different pressures, two boilers, one adapted to generate steam of a higher pressure than the other, which latter is a smoke tube boiler, two separate superheaters located in the smoke tubes of the last-mentioned boiler, a connection for conveying steam from the high pressure boiler to one of said superheaters and from such superheater to one stage of the engine, another connection for leading steam from the low pressure boiler to the second superheater and from the latter to a subsequent stage of the engine, and a third connection for conducting the exhaust steam from the first mentioned stage to said subsequent stage without passing through the second superheater.

7. In a locomotive as claimed in claim 6, a device located in the connection from the exhaust of the first mentioned stage to the subsequent stage, for preventing such exhaust steam from passing into the superheater which is connected with the low pressure boiler.

In testimony whereof I have hereunto set my hand.
